UNITED STATES PATENT OFFICE.

SAMUEL C. ARNOLD, OF DENVER, COLORADO, ASSIGNOR TO THE DENVER QUARTZ MILL
AND CRUSHER COMPANY, OF DENVER, COLORADO.

ROCK-CRUSHER.

1,109,158.

Specification of Letters Patent.

Patented Sept. 1, 1914.

Application filed July 18, 1910. Serial No. 572,450.

To all whom it may concern:

Be it known that I, SAMUEL C. ARNOLD, a citizen of the United States of America, residing at Denver, in the county of Denver and State of Colorado, have invented 5 certain new and useful Improvements in Rock-Crushers, of which the following is a specification.

My invention relates to new and useful 10 improvements in ore-crushers of the type in which a movable jaw has a reciprocating movement relative to a fixed jaw and its principal object resides in the provision of a pair of coöperative jaws and a therewith 15 associated mechanism by means of which ore fed between the jaws is speedily reduced to a fineness of uniform size. With this end in view I have provided an operating mechanism which compels the lower end of the 20 movable jaw to move in correspondence with its upper extremity so that the angle between the working face of said movable jaw and that of the stationary jaw remains substantially unchanged while the former 25 is in motion, and the said working faces are formed and arranged with relation to each other so as to compel the ore fed between them to move downwardly while being crushed and to subject the same to two 30 distinct successive crushing actions before it is discharged from the machine.

Other objects of my invention are fully disclosed in the following description, reference being had to the accompanying drawings 35 in the various views of which like parts are similarly designated and in which,

Figure 1 represents a central vertical section through the machine and Fig. 2, a plan view of the same.

Referring to the drawings, the numeral 2 40 designates the frame of the machine, including the parallel upright sides 3 between which the operating parts comprised in the construction are supported.

The numeral 4 denotes the stationary jaw 45 which is rigidly secured between the sides 3, in an inclined position, by means of transverse rods 5 which extend through registering bores in the upper and lower ends of 50 the jaw and the sides of the frame and whose extremities protrude beyond the outer surfaces of the latter. The jaw 4 is formed with a transverse mortise for the reception of a correspondingly shaped tenon 6^a on a 55 chilled iron face plate 6 which covers the

upper surface of the jaw and whose extreme portions extend in angular relation to its main, central portion. The lower one of these end portions, designated in the drawings by the numeral 6^c, extends parallel and 60 in close proximity to the working face of the chilled face plate 7 of the movable jaw 8 which at its upper extremity is suspended from the eccentric, central portion of a crank shaft 9.

A box 8^a movably disposed in a correspondingly formed guide way in the jaw 8 is supported upon two cotters 14 the threaded extremities of which are provided with nuts 14^a which serve to vertically adjust the 70 position of the box 8^a, in the jaw by drawing the cotters longitudinally through the ways in the jaw in which they are disposed.

The crank shaft 9 whose eccentric portion occupies the box 8^a, is rotatably supported in journal boxes 10 at the upper end of the frame 2 and it carries upon its protruding ends, fixed and loose pulleys 12 and fly wheels 13 for the usual purposes.

The jaw 8 is connected at its lower extremity with the end of a horizontally disposed rod 15 which projects through an opening in the end plate 3^a of the frame and which is provided at its outer, threaded extremity with a nut 16. A spring 17 coiled 80 around the rod 15 between the nut 16 and the outer surface of the plate 3^a, serves to maintain the moving jaw resiliently in engagement with an abutment the construction of which will now be described.

A block 18 which is horizontally slidably mounted between guides 19 formed integral with the sides 3 of the frame, carries a transversely disposed rod 20 the extremities of which project through horizontal slots 21 95 in the said sides. A toggle block 23 is horizontally slidably supported between guides 24 on the sides of the frame, and the two blocks are connected by means of two plates 22 which project loosely through slots in 100 the abutment block and which carry shearing pins 26 which engage the face thereof. The toggle block 23 which is engaged at one of its sides by the plates 22, is grooved at its opposite side to receive the extremity 105 of a toggle 25 whose other end engages a die 8^c set in a recess in the lower portion of the moving jaw 8.

The protruding ends of the rods 5 which secure the fixed jaw 4 between the sides 3 110

of the frame, project through circular eyes formed at the extremities of U-shaped yokes 27 which, being arranged exteriorly with relation to the frame, embrace the protruding portions of the rod 20 on the abutment block 18. Bolts 28 which project through threaded apertures in the bent portions of the yokes 27, engage the ends of the rod 20 embraced thereby, for the purpose of 10 adjusting the position of the block 18 and the therewith associated jaw 8, relative to the fixed jaw 4.

Having thus described the mechanical construction of the crusher, its operation 15 and the advantages derived therefrom will be readily understood.

The ore to be reduced is fed between the two jaws and the sides of the frame 2 which as usual are provided with cheek plates 29.

20 The working face of the face plate 7 of the movable jaw 8 extends parallel and in juxtaposition to the portion 6° at the lower extremity of the working face of the fixed jaw 4 and it is inclined from the perpendicular toward the latter so that the ore while being crushed by the action of the moving jaw is at the same time compelled to move downwardly.

25 The crank shaft 9 when rotated, imparts to the upper portion of the jaw 8 a circular movement about a fixed transverse axis, while the lower portion of the jaw moves correspondingly by reason of the inclined position of the toggle 25 the extremities of 30 which engage the die 8° and the toggle block 23. The result is that the angle between the working faces of the two jaws remains substantially unchanged and the crushing action upon the rock fed between 35 the same is produced by a direct lateral movement of the jaw 8 toward the fixed jaw combined with a downward grinding motion. After the rock has been reduced 40 between the upper portions of the two jaws it is further comminuted to a fineness of uniform size between the portion 6° of the face of the fixed jaw and the therewith engaging lower part of the face of the movable jaw.

45 The yokes 27 which hold the abutment 18 against rearward motion, receive the greater part of the strain to which the crusher-frame is ordinarily subject and the latter may, for this reason, be constructed of lighter material to reduce the weight and 50 cost of manufacture of the machine.

55 The bolts 28 afford ready means for the

adjustment of the moving jaw relative to the fixed jaw 4 and should any part of the machine be subjected to more than ordinary stress, the shearing pins 26 will prevent 60 breakage of more important and less readily replaceable elements of the structure. It will be observed that the chilled face plates of the two jaws are so formed that, when the lower portions are worn, their position 65 on the jaws may be readily reversed.

Having thus described my invention what I claim and desire to secure by Letters-Patent is:—

1. In a rock crusher, a frame including 70 parallel side plates provided with opposite slots, fixed and movable jaws between said plates, means for imparting a circular movement to the upper portion of the movable jaw, an abutment having projections slidingly extending through the said slots, a toggle connection between said abutment and the lower portion of the movable jaw, a spring disposed to maintain the latter yieldingly in engagement with the said 75 toggle, and yokes connected with the protruding portions of the said projections and secured at separate points at the upper and lower portions of the frame at its end at which the stationary jaw is located to receive the stress caused by the crushing force in the operation of the machine.

2. In a rock crusher, a frame including 90 parallel side plates provided with opposite slots, fixed and movable jaws between said plates, means for imparting a circular movement to the upper portion of the movable jaw, an abutment having projections slidingly extending through the said slots, a toggle connection between said abutment 95 and the lower portion of the movable jaw, a spring disposed to maintain the latter yieldingly in engagement with the said toggle, yokes embracing the protruding portions of the said projections at opposite 100 sides of the frame and connected at their extremities with the upper and lower ends of the stationary jaw, and adjustment screws extending through apertures in the yokes in engagement with the said projections. 105

In testimony whereof I have affixed my signature in presence of two witnesses.

SAMUEL C. ARNOLD.
